FAUCET HANDLE

Ralph E. Thorp, Lafayette, Ind., assignor to
Globe Valve Corporation

Filed Feb. 3, 1972, Ser. No. 223,394

Term of patent 14 years

Int. Cl. D23—01

U.S. Cl. D23—28

FIG. 1

FIG. 2

FIG. 3

FIG. 1 is a top plan view of a faucet handle showing my new design;

FIG. 2 is a side elevation view, all sides being the same; and

FIG. 3 is a fragmentary sectional view taken along line 3—3 of FIG. 1.

I claim:

The ornamental design for a faucet handle, substantially as shown and described.
